FIG. 3.

FIG. 4.

H.R.HUGHES, Inventor

By His Attorney *Jesse P. Stone*

UNITED STATES PATENT OFFICE.

HOWARD E. HUGHES, OF HOUSTON, TEXAS.

ROTARY BORING-DRILL.

1,255,422.

Specification of Letters Patent. Patented Feb. 5, 1918.

Application filed November 5, 1917. Serial No. 200,266.

To all whom it may concern:

Be it known that I, HOWARD R. HUGHES, a citizen of the United States, residing at Houston, Harris county, Texas, have invented a certain new and useful Improvement in 5 Rotary Boring-Drills, of which the following is a full, clear, and exact description, such as will enable others skilled in the art to which it appertains to make and use the 10 same.

My present invention relates to improvement in rotary boring drills of the roller type, but more especially to the disk form of roller bit designed for drilling oil or water 15 wells. This type of bit is commonly operated on a rotating drill stem actuated from a suitable source of power at the surface. The drill stem is a hollow pipe through 20 which water is forced by a pump, or other means, from the surface down to the drill, the water issuing therethrough upon the bottom of the hole. The cuttings and disintegrated material loosened by the drill are flushed away by this water and are carried 25 upwardly outside the drill stem to the surface. In drilling in soft formation, such as clay and gumbo, a great deal of trouble is often encountered by drillers through the 30 tendency of a rotary drill to ball up with the disintegrated clay and gumbo. In such cases the cutters on a rotary bit will clog up with the clay and fail to work. When the bit is withdrawn from the well the cutting 35 disks are found to be packed tightly about by a mass of wet clay, so that the bit presents somewhat an appearance of a mushroom, the lower cutting end being rounded off by the packed material and leaving no means of drilling farther.

40 It is to avoid this objectionable balling up that my present invention was devised. My plan is to start the drilling with the head of the bit rounded off at the base in the manner of a balled up bit, and arrange the 45 cutters in the head so that they cannot be clogged up by the detritus, the flushing water issuing in such manner as to keep the cutters always clear.

One object of my invention is to construct 50 the head of a rotary disk drill in such form that it will not easily ball up in soft material.

Another object is to arrange the channel for the flushing water in such manner that the cutters will be kept clear and the water 55 will also be directed immediately upon the portion of the hole being cut by the bit.

Other objects and advantages of my invention will more clearly appear in the description which follows:

Referring to the drawings, which form a 60 part of this specification, Figure 1 is a front view partly in section of my invention. Fig. 2 is a side view of the same; Fig. 3 is a bottom plan view thereof with one cutter removed, and Fig. 4 is a top plan view similar 65 to Fig. 3.

My improved drill head comprises a main body portion preferably cylindrical in shape, having an upwardly extending threaded shank, 2, for attachment to the drill stem, 70 not shown. The lower end of the head is rounded off so that it presents the hemispherical appearance common to a balled up bit. Two parallel vertical slots, 14, are cut in the lower rounded end to provide a housing 75 for rotatable cutting disks, 5. These slots leave a central flat supporting member, 4, extending down between the slots to conform to the hemispherical shape desired in the head, and two side supporting legs 3, 3 80 also rounded off as described.

The cutting disks are mounted opposite each other on a straight bearing pin, 6, having one end reduced somewhat and threaded as at 7 for attachment in the threaded opening in the leg 3. The shoulder, 8, thus provided on said pin contacts with the inner flat side of the outer-leg, 3, as shown in Fig. 1 when the pin is tightened into place. The bearing pin, 6, is secured in place against 90 accidental loosening thereof by a tapered pin, 9, which is secured into a tapering hole in the central support, 4, at right angles to the bearing pin, and passes into a recess in the pin, as shown in Figs. 1 and 2, preventing lateral movement of said bearing pin in an obvious manner.

The tapered hole for the pin is enlarged at one end as at 10 to allow the pin to be driven out, and is also enlarged at the opposite end and threaded to provide a seat for a set screw, 11, which holds the pin in its seat when the pin is properly driven in place.

The circular flat cutting disks are housed in their respective slots closely adjacent to 105 the walls thereof. The upper walls of the slots are grooved in an arc to conform to the shape of the cutters, the outer side being extended downwardly to partially shroud the cutters as at 12. Non-friction 110 washers 25 and 24 are provided on the inner and outer flat sides, respectively, of the

disks. These washers are comparatively large and project from the sides of the cutters sufficiently to fill up the slots at each side of the disks. The cutters are larger on 5 their inner diameter and are toothed on their peripheral surfaces, said teeth being cut at an angle to the edge of the disk, as shown at 13. The teeth thus slant downwardly from the smaller diameter toward 10 the larger one on the forward side of the disk, thus providing an efficient cutting edge adapted to dig rapidly into the material.

The flushing water is conducted from the upper part of the head inside the drill stem 15 through two inclined passages or ducts, 15, to the cutters. These passages converge at a point, 16, on a level with the upper edge of the slots, 13, and from this point a passage, 17, extends laterally to each of the 20 said slots. On the opposite side of the slot 14 from the passage 17 and somewhat offset therefrom toward the rear of the cutter is a downwardly extending duct or groove, 18. Said groove is adapted to catch the water 25 issuing from the passage, 17, and conveys the same out the lower end of the bit. It is to be noted that the water, as it issues from the passage 17, across the top of the slot, passes between the inclined teeth of the 30 cutter, being thus directed somewhat to the rear of said cutter so as to pass into the upper end of the downwardly extending duct, 18. Said groove or duct, 18, is formed on the inner surface of the outer leg, 3, and 35 issues at the lower end thereof so that the water is projected immediately upon the bottom of the hole.

The cutters are lubricated in the usual manner. The lubricator, not shown, is 40 screwed upon the threaded shank, 19, at the central upper end of the head. Oil from the lubricator passes downwardly through a central duct, 20, to lateral passages, 21, leading to the bearing pin. The said pin 45 is grooved, as at 23, and provided with ducts, 22, to feed the oil upon the cutters in an obvious manner.

In the operation of my bit the head is rotated in a clockwise direction. The toothed 50 cutters, 5, roll on the bottom of the hole due to the friction between the cutter and the said bottom. The cutter also has a shearing or cutting action, the sharp edge of the disk scraping or shearing off the material of the 55 bottom of the hole. The material thus disintegrated is washed away from the cutters by the action of the flushing water issuing from the passages, 18, and impinging directly upon the work.

60 Any material clogging in the teeth of the cutter is partially cleaned off by the scraping of the material against the shroud or housing at 12 as the cutter turns. The tooth then comes in the path of the flushing 65 stream at 17. The water is projected with

force against the said material and washes it clean from the teeth, said material being carried with the water downwardly through the passage, 18, to the bottom of the hole. The manner in which the cutter is closely 70 housed in the slot leaves no room for the passage of the flushing water around down the flat sides of the disk. Some small part of the water may escape around the periphery of the cutting teeth, but the main volume of the water must pass directly across the top of the disks and issue from the downwardly extending passage, 18.

It will be apparent that the disk-shaped cutters will dig a cup-shaped hole into which 80 the hemispherical head will closely fit.

I have thus provided a head, the cutters of which will not ball up. Due to the fact that the head conforms to the shape of the bottom of the hole, there is no chance for 85 the clay to wedge or pack around the cutters to clog their action. Any clay or other material which gathers in the teeth of the cutters is washed away by the flushing stream which is projected directly upon it, 90 leaving the teeth at all times clean and easily operated.

Having thus described my invention, what I claim as new and desire to protect by Letters Patent is:

1. A rotary boring tool comprising a head, the forward end thereof being rounded to conform to the shape of the hole; two cutters housed in separate slots in the forward rounded end of said head, said cutters being 100 on axes at right angles to the longitudinal axis of the head.

2. A rotary boring tool comprising a head, the forward end being hemispherical in shape, vertical slots cut in the rounded end 105 thereof, cutting disks mounted in said slots, and means to direct flushing water directly in advance of the tool.

3. A rotary boring tool comprising a head, the forward end thereof being hemi- 110 spherical in shape, two vertical cutting disks mounted in slots in the forward rounded end of the head, said disks housed closely within said slots, and water passages in said head arranged to direct the flushing water 115 across the periphery of the disks and also upon the bottom of the hole being drilled.

4. In a rotary boring drill, a head, the forward end thereof being rounded to conform to the shape of the hole, two vertical 120 cutting disks mounted in slots in the forward end thereof, said cutters being opposite and housed closely within said slots in such manner as to prevent material from entering said slots, and adapted to act simultaneously on both sides of the hole.

5. In a rotary boring tool, a head, cutters housed in slots in the lower end thereof, water ducts for directing the flushing water across the upper part of said slots, chan- 130

- nels in the side of said slots offset from the said ducts to convey the water directly upon the bottom of the hole.
6. In a rotary boring drill, a head, cutters housed in slots in the forward end thereof, inclined teeth on said cutters, water ducts in said head to direct the flushing water between said inclined teeth and offset downwardly extending water channels to conduct the water out the forward end of said head.
7. A rotary boring drill, comprising a head, cutters housed in slots in said head arranged to direct the flushing water across the upper part of said slots, channels extending downwardly therefrom to conduct the water directly on to the bottom of the hole being drilled.
8. A rotary boring drill, comprising a head, the lower end thereof being rounded into hemispherical shape, cutting disks mounted closely in slots within said rounded end, water ducts in said head arranged to direct the flushing water across the upper periphery of said cutters, and channels offset from said ducts to convey the water directly upon the material being drilled.
9. A rotary boring drill, comprising a head, the lower end thereof being rounded into hemispherical shape, cutters housed in slots in the forward end of said rounded head, inclined teeth on said cutters, water ducts in said head to direct the flushing water between said inclined teeth at the upper part of said slots and downwardly extending water channels to conduct the water from said teeth to the bottom of the hole being drilled.
10. A rotary boring drill comprising a head, flat cutting disks housed in the forward end thereof adapted to cut a cup-shaped hole, the forward end of said head being rounded to conform to the shape of the hole, two inclined water channels in said head, said channels converging at the center of the head, lateral channels to direct the water across the upper part of said disks, and downwardly extending grooves to conduct the water on to the bottom of the hole.
11. A rotary boring tool comprising a head, the forward end thereof being hemispherical in shape, cutting disks mounted in the rounded end of said head on an axis at right angles to the longitudinal axis of the head, said cutters projecting a short distance from each side of the head so as to act simultaneously on both sides of the hole.
12. A rotary boring tool comprising a head, cutters housed in the forward end thereof, teeth on said cutters and water ducts in said head arranged to direct flushing water laterally across the upper part of said housing and between the teeth of said cutters for the purpose specified.
13. A rotary boring drill comprising a head, disk-shaped cutters mounted in slots in the forward end thereof, teeth on said cutters and water ducts in said head arranged to direct the water laterally across the upper end of said slots and between the teeth of said cutters to wash the same free from the loosened material cut by the drill.
14. A rotary boring tool comprising a head, cutters housed closely in the forward end thereof, teeth on said cutters and water ducts in said head arranged to direct flushing water laterally across the upper part of said housing and between the teeth of said cutters and downwardly directed channels to conduct the water from thence directly upon the bottom of the hole being drilled.

In testimony whereof, I hereunto affix my signature this the 10th day of October, 1917.

HOWARD R. HUGHES.
